UNITED STATES PATENT OFFICE.

WILLIAM M. STINSON, OF LOUISVILLE, KENTUCKY.

DESIGN FOR A DIAPER.

SPECIFICATION forming part of Design No. 31,570, dated September 26, 1899.

Application filed July 27, 1899. Serial No. 725,329. Term of patent 7 years.

To all whom it may concern:

Be it known that I, WILLIAM M. STINSON, of Louisville, in the county of Jefferson and State of Kentucky, have invented and produced a new and original Design for a Diaper, of which the following is a full, clear, and exact description.

Reference is to be had to the accompanying drawing, forming a part of this specification, in which the figure is a plan view of a diaper, showing my design.

The design in its entirety consists of a middle portion A and integral end pieces B and C, extending beyond both sides of the shank,

with the end piece arched at its outer edge B' 15 and half-round at the sides B², the outer edge C' of the end piece C being straight and the sides rounded off, as at C², and the end piece appearing with cuts D to form flaps.

The leading feature of my design consists 20 of the shank and the end pieces.

I claim—

The design for a diaper herein shown and described.

WILLIAM M. STINSON.
